THOMAS S. HOMANS, OF HEMPSTEAD, NEW YORK, ASSIGNOR TO INTERNATIONAL TYPESETTING MACHINE COMPANY, OF NEW YORK, N. Y., A CORPORATION OF NEW YORK

KEYBOARD MECHANISM FOR LINE-COMPOSING MACHINES.

1,102,923.

Specification of Letters Patent.

Patented July 7, 1914.

Application filed March 11, 1913. Serial No. 753,593.

To all whom it may concern:

Be it known that I, THOMAS S. HOMANS, a citizen of the United States, residing at Hempstead, in the county of Nassau and State of New York, have invented new and useful Improvements in Keyboard Mechanism for Line-Composing Machines, of which the following is a specification.

The present invention relates to improvements in line composing machines and more especially to those of the well known linotype class, and the invention pertains to the keyboard mechanism whereby manipulation of the finger keys thereof controls the actuation of power-operated cam yokes which cam yokes transmit corresponding movements to escapement devices, the latter controlling the delivery of matrices from different matrix-containing channels of the magazine.

The primary object of the invention is to provide novel and improved bearings for the cam yokes, such bearings enabling any one or more of the yokes to be removed, together with its individual or respective bearing, from the machine for any purpose, such, for example, as lubrication, cleaning or repairing, the removal of one or more of the cam yokes not affecting the remaining cam yokes.

To this end, the invention consists in certain improvements, and combinations and arrangements of parts, all as will be herein-after more fully described, the novel features being pointed out particularly in the claims at the end of the specification.

In the accompanying drawing:—Figure 1 is a perspective view of a section of the keyboard mechanism of a machine constructed in accordance with the present invention, it being understood that only a few of the operative parts of the keyboard mechanism are shown; Fig. 2 is a perspective view showing another method of holding the cam yoke bearings in operative position.

Similar parts are designated by the same reference characters in the several views.

The present invention is applicable generally to any style of machine employing a keyboard of this class, and it is to be understood that the claims at the end of this specification are not limited to a machine of any particular type, although the invention

is illustrated and will be described as applied to keyboard mechanism of the same type as that disclosed in my prior application, Serial No. 707,926, filed July 5, 1912.

In the present instance 1 designates a few of the key levers of the keyboard, these key levers being usually pivoted, as shown, and provided at their forward ends with finger keys which are adapted to be manipulated in the usual way by the fingers of the operator. The rear ends of the key levers are operatively connected to corresponding vertically movable key bars 2, the latter being suitably guided in the frame of the machine and are lifted when the corresponding finger keys are depressed. These key bars co-operate with corresponding triggers 3, the latter being mounted to rock on the pivot pin 4 supported by the frame of the machine, each trigger having a substantially horizontal arm which co-operates with the respective key bar and a vertical or upwardly projecting arm which controls the operation of the respective cam yoke. The cam yokes 5 may be of the usual or any desired construction, although the present invention provides improved pivotal bearings therefor. According to the present invention, an individual bearing 6 is provided for each cam yoke, each bearing being formed preferably with a slot 7 to receive the corresponding end of the respective cam yoke, and a pivot pin 8 is provided which forms a pivotal connection between each yoke and its respective bearing. In the construction shown, each bearing has a lower reduced portion forming a shank 9 which may be cylindrical so as to fit removably in a bore 90 formed in a stationary supporting bar 10, the bearings for the different yokes in the present instance being arranged in a longitudinal row in the bar 10 and may be inserted and removed from the top thereof.

The cam yokes carry cams 11 which, in the present instance, are pivoted to rotate in hollow chambers 12 in the yokes and these cams are arranged above a continuously revolving power-operated roller 13. The cams are provided with pins or projections 14 and a bar 15 is fixed to the stationary framework 16 and provides downwardly extending teeth or projections 17 against

which the projections 14 on the respective cams normally rest, the cams being thereby held out of contact with the surface of the revolving roller 13.

5 The triggers 3 normally support the cam yokes in such positions that the projections 14 on the cams will rest against the teeth or projections 17, the cams at this time being out of contact with the revolving roller and hence the parts will be inactive. Depression of any one of the finger keys of the keyboard, however, will cause upward movement of the corresponding key bar and that key bar will rock the corresponding trigger 3 into a position where its upwardly extending arm moves from beneath the corresponding cam yoke and into the hollow portion thereof, thereby allowing such cam yoke to drop and dropping of the cam yoke will 20 carry the projection 14 of the respective cam downwardly and out of contact with the respective tooth or projection 17 and will cause the respective cam to rest on the top of the revolving roller. The revolving motion of the roller will then cause rotation of this cam and the cam is so shaped that when rotated it will elevate the cam yoke. The upward movement of the cam yoke under the action of its cam is transmitted by suitable means to the escapement which controls the delivery of corresponding matrices from the magazine, plungers 18 being shown in the present instance which operate vertically through guides 19 fitted in the frame member 20, and the upper ends of these plungers cooperate with vertically movable reeds 21, the latter operating in the usual or any suitable way upon the matrix-controlling escapements. After each cam has actuated 25 its cam yoke to effect the delivery of the selected matrix from the magazine, such cam returns to a position where its projection 14 rests against the corresponding tooth or projection 17, the cam being then out of contact with the revolving roller 13 and the cam will rest upon its trigger, the latter being restored to normal position when pressure upon the corresponding finger key has been relieved by the operator.

30 Means is provided for retaining the bearings for the cam yokes in proper operative position although enabling any one or more of these bearings to be easily and quickly removed together with its cam yoke and cam when such is desirable or necessary. In Fig. 1, a bar or keeper 22 is provided, it being pivotally supported in any suitable way, such, for example, as by the pin or rod 23 carried by the framework 16, and a stop 24 is provided for supporting the keeper when swung into an inoperative position. This bar or keeper preferably occupies normally a vertical position with its lower edge resting on or positioned immediately above the tops of the cam yoke bearings 6, the bear-

ings being thereby held in their normal operative positions. When it is desirable or necessary to remove any one of the cam yokes, the keeper is swung out of its operative position and, for example, into the position indicated by the dotted lines in Fig. 1, the keeper then resting against the stop 24 and any one or more of the bearings can be lifted or removed from the bar 10. Return of the keeper to the full-line position locks all the bearings in position. Instead of using a bar or keeper such as that just described for retaining the bearings in place, other means may be used, such, for example as shown in Fig. 2, wherein set-screws 25 80 coöperate with the stems or shanks of the corresponding bearings and thereby retain them in the bar 10.

The present invention provides simple and improved means whereby any one or more of the cam yokes may be easily and quickly removed and replaced, and in employing removable cam yoke bearings embodying the present invention, it is unnecessary to slot or otherwise cut away any portion of the pivot bearing in the cam yoke and hence such bearing is capable of withstanding wear to the best advantage.

I claim as my invention:

1. Keyboard mechanism for line composing machines embodying, in combination, a frame, a plurality of key-controlled power-actuated devices, a plurality of bearings pivoted to the corresponding power-actuated devices and mounted in the frame, each of 95 said devices and its corresponding bearing being removable as a unit from the frame independently of the remainder.

2. Keyboard mechanism of the class described embodying a frame, a series of cam 105 yokes, and a series of bearings each pivotally connected individually to a corresponding cam yoke of the series and mounted on said frame, each of said bearings being removable from the frame independently of the 110 other bearings.

3. Keyboard mechanism of the class described embodying a frame, a cam yoke, and a bearing individually and, pivotally connected to said cam yoke and removably 115 fitted to said frame, the yoke and its bearing being removable as a unit.

4. Keyboard mechanism of the class described embodying a frame, a series of cam yokes, a series of bearings pivotally connected to the corresponding yokes of the series and capable of removal individually with the respective cam yoke from said frame, and means for preventing removal of the bearings from the frame.

5. Keyboard mechanism of the class described embodying a frame having a socket, a cam yoke, and a bearing having a portion removably fitting said socket in the frame and pivotally connected to the cam yoke.

6. A keyboard mechanism for machines of the linotype class, in combination, a frame, a series of cam yokes having individual pivot-carrying bearings, each bearing and cam yoke being demountable from the frame independently of the remaining bearings and yokes.

In testimony whereof I have hereunto set my hand in presence of two subscribing witnesses.

THOMAS S. HOMANS.
